Primary Examiner — John Windmuller*Assistant Examiner* — Steven J Czyz(74) *Attorney, Agent, or Firm* — Alan D. Kamrath; Kamrath IP Lawfirm, P.A.(57) **CLAIM**

The ornamental design for an underarm crutch, as shown and described.

DESCRIPTION

FIG. 1 is a perspective view of an underarm crutch showing our new design;
 FIG. 2 is another perspective view thereof;
 FIG. 3 is a front elevation view thereof;
 FIG. 4 is a rear elevation view thereof;
 FIG. 5 is a left side elevation view thereof;
 FIG. 6 is a right side elevation view thereof;
 FIG. 7 is a top plan view thereof; and
 FIG. 8 is a bottom plan view thereof; and
 FIG. 9 is a perspective view of the underarm crutch shown in an alternate state.
